UNITED STATES PATENT OFFICE

BEDROS GIRAGOSIAN, OF WATERTOWN, MASSACHUSETTS

WATER HEATER

Application filed February 23, 1928. Serial No. 256,133.

This invention relates to a water-heating device and particularly to one in which a candle may be used for the heating element.

One of the objects of the invention is to provide an improved water heater which is relatively simple in construction but which is efficient in operation.

Another object of the invention is to provide an improved water-heating device which is constructed so that it may be used just as effectively when the candle is pretty well burned as when the candle is of full length.

Other objects of the invention are to improve generally water heaters in various ways all as will be more fully hereinafter set forth.

In order to give an understanding of the invention I have illustrated in the drawings a selected embodiment thereof which will now be described after which the novel features will be pointed out in the appended claim.

Fig. 1 is a vertical sectional view of a water heater embodying my invention and illustrating the device in use with a full length candle;

Fig. 2 is a similar view illustrating the device as it would be used when the candle is partially burned;

Fig. 3 is a section on the line 3—3, Fig. 1; Fig. 4 is a reduced perspective view illustrating the cover or housing in which the device is enclosed.

My improved device comprises a housing indicated generally at 1 and formed in three sections, to wit, a base section 2, an intermediate section 3 and an upper water-holding section 4, the latter being provided with a receptacle or cup portion 5 to receive water or other liquid to be heated. The heating of the liquid is accomplished by the burning of a candle 6 which is located within the housing 1. This candle is shown as being supported by a candle holder 7 which is adapted to be received within the base section 2 of the housing.

The water receptacle or cup 5 may conveniently be formed as an integral part of the upper section 4 although the invention would not be departed from if this receptacle 5 was separate from the section 4 and removably

supported thereby. The intermediate section 3 is separable from the base section 2 and the upper water-holding section 4. Said intermediate section is in the form of a sleeve, the lower portion 8 of which telescopes over the upper end 9 of the base section 2. This upper end 9 is shown as being slightly reduced in diameter so as to fit within the lower end 8 of the intermediate section 3, said base section being formed with the shoulder 10 on which the intermediate section 3 is supported. Similarly, the upper end 11 of the intermediate section is somewhat reduced in diameter so that it will fit within the lower end of the upper section 4.

The intermediate section 3 is provided with openings 12 and the upper end 9 of the base section which fits within the intermediate section is similarly provided with other openings 13. The openings 12 and 13 have the same relative position so that when the parts are assembled they will register with each other and thus suitable draught openings are provided for supplying air to support combustion of the candle.

The intermediate section 3 can be turned on the base section 1 so as to close the openings more or less thereby providing for admitting the correct amount of air to the interior of the housing to properly support combustion and prevent the candle from smoking.

The upper section 4 is provided at its upper end with vent openings 14 through which the products of combustion escape.

The side walls of the receptacle 5 are preferably tapered somewhat as shown and when the candle is in position and is lighted the hot gases of combustion will strike against the bottom of the receptacle and will flow up around the inclined sides thereof thus effectively heating any material in the receptacle.

The candle holder 7 is shown as having a depending tab 15 which extends through an opening in the bottom of the base section 2. Said tab is provided with an opening to receive a locking pin 16 that is situated beneath the bottom 17 of the base section 2. By this means the candle holder is firmly locked in position. The base member will preferably be provided with a down-turned 100

flange 18 on which the housing rests and which supports the bottom 17 sufficiently above the table or support so that the tab 15 will not engage therewith.

5 I have stated above that the intermediate section 3 is removable and when it has been removed the upper or water-holding section 4 may be applied directly to the base section 2, as shown in Fig. 2, thus lowering the cup. 10 When the candle is full length the intermediate section 3 will be used as shown in Fig. 1 but when the candle gets partially burned so that the flame 19 is so far removed from the bottom of the receptacle that it does not 15 readily heat the water or other liquid therein then the section 3 may be removed and the upper section 4 placed directly on the base section. When this has been done the receptacle is brought into a position where it will 20 be effectively heated by a partially-burned candle as shown in Fig. 2.

The lower end of the upper section 4 is provided with openings 20 which are spaced similarly to the openings 13 so that when 25 the parts are assembled as shown in Fig. 2 there will still be the proper draught openings for supporting combustion.

To facilitate transporting the device when filled with hot water I have provided a bale member or handle indicated generally at 21. 30 This may conveniently be made of wire and each of the two legs 22 thereof is bent inwardly at its lower end as shown at 23. These inwardly-bent ends 23 may be inserted 35 in two opposed openings 14 as illustrated in Figs. 1 and 2 so that the handle 21 will function as a bale by which the device may be transported from one location to another. This handle or bale member is preferably 40 of such a size that it may be placed inside the cup portion 5 as shown by dotted lines in Fig. 1 at such time as the device is not being used.

24 indicates a cover member in which the 45 housing 1 may be placed when the device is not being used. The base member 2 is shown as having screw threads 25 formed thereon at its lower end and the cover 24 is of a size to telescope over the housing and is provided at 50 its lower open end with interior screw threads 26 adapted to screw onto the screw threads 25 as shown by dotted lines in Fig. 1. The cover 24 is closed at its upper end so that 55 when it is screwed onto the screw threads 25 the device is entirely enclosed therein.

The device can be very inexpensively made and furnishes an efficient way of heating small quantities of water or other material. It is especially advantageous for use in those 60 locations where gas or other means of heating is not available.

While I have illustrated a selected embodiment of my invention I do not wish to be limited to the constructional features shown 65 and various changes may be made in the de-

tails of the device without departing from the invention.

I claim:

A water heater comprising a housing presenting a base section, an intermediate section and an upper section, a cup or receptacle carried by the upper section, a candle holder located in the base section and adapted to support a candle for heating material in said cup, said intermediate section being separable from the base section and the lower end of the intermediate section telescoping over the upper end of the base section, the overlapping portions of said two sections being provided with draft openings, the size of which may be varied by turning the intermediate section relative to the base section, the upper section being separable from the intermediate section and the lower end of the upper section being of a size to telescope over either the upper end of the intermediate section or the upper end of the base section, said lower end of the upper section being also provided with draft openings which are closed by the upper end of the intermediate section when the upper section is supported by the intermediate section but which register with the draft openings of the base section when the upper section is applied directly to the base section, whereby the housing may be constituted by all three sections or by the upper section and base section only dependent on the length of the candle being used.

In testimony whereof, I have signed my name to this specification.

BEDROS GIRAGOSIAN.
